THREAD ADVANCING DEVICE

Harry A. Kuljian, Merion, Pa., assignor to The Kuljian Corporation, Philadelphia, Pa., a corporation of Pennsylvania

Application August 2, 1948, Serial No. 41,973

8 Claims. (Cl. 28—71.5)

1

In the manufacture of synthetic thread, or in the processing of synthetic or natural threads, a thread advancing device is used for causing the thread to move through a predetermined distance, during a predetermined time. One form of thread storing and advancing device includes a plurality of elongated, skewed rolls, and means for rotating said rolls about their longitudinal axes. The thread is applied to a device of this type by winding the end of the thread a few times about one end of said device. The operation of applying the thread to the thread storing and advancing device is referred to as lacing and one object of the invention is to produce improved apparatus for, and an improved method of, lacing a thread onto a thread advancing device.

In some instances, the thread advancing device includes a relatively large number of rolls and is supported at both ends thereof. To lace a thread onto a device of this type by manually winding the end of the thread around the exterior of all of the rolls is very difficult.

In other instances, the thread advancing device is supported in cantilever manner and the operator can stand near the free end of the device and can reach over and wind the thread as near to the other end of the device as possible. However, when a cantilever supported thread storing and advancing device is relatively long or has a relatively large diameter, or both, the lacing operation again becomes very difficult.

It is therefore a further object of the invention to produce an improved apparatus for, and method of, lacing the end of a thread onto a thread advancing device whereby the lacing operation is greatly facilitated, regardless of whether the thread advancing device is supported at both ends or not and regardless of the length or of the diameter of such device.

A still further object of the invention is to produce an improved lacing apparatus which is semi-automatic, which is inexpensive, which is durable and which can be operated with minimum skill and effort.

When the relatively large number of thread storing and advancing devices which are used in an average size mill is considered, it will be seen that lacing the threads onto said devices is responsible for a substantial portion of the unit cost of production and therefore improvements which simplify or expedite the lacing operation will contribute very materially to the advance of the industry.

The manner in which my improved lacing device 55 of the rolls are so skewed that a thread laced

2

vice and my improved method of lacing are carried out will be understood from the following specification and the accompanying drawings in which:

5 Fig. 1 is a fragmentary and diagrammatic side elevational view of a thread manufacturing or treating apparatus embodying my invention, certain parts being omitted, the thread advancing and storing device being mounted in cantilever fashion.

Fig. 1A is a view looking in the direction of line 1A—1A showing the parts omitted from Fig. 1.

Fig. 2 is an enlarged, fragmentary sectional view on line II—II on Fig. 1.

15 Fig. 3 is a fragmentary and diagrammatic view, looking in the direction of line III—III on Fig. 1, illustrating the ineffective position of the lacing device embodying my invention.

Fig. 4 is similar to Fig. 3 showing the effective position of the lacing device.

20 Fig. 5 is an elevational view showing a form of linkage for actuating the lacing device from one of its positions to the other.

Fig. 6 is similar to Fig. 1 except that it shows 25 the application of the invention to a thread manufacturing or treating apparatus of the type in which the thread storing and advancing device is supported at both of its ends.

30 A synthetic thread manufacturing apparatus of the type shown in Fig. 1 includes a supporting frame 10, an inner end plate 12 carried by said frame, a central fixed post 14 carried by said end plate, an outer end plate 16 carried by said fixed post, and a plurality of rolls, R1, R2, R3, R4, R5, R6, R7 and R8, arranged in a circle about the fixed post 14 and having their ends journaled for rotation in self aligning bearings 17 provided in said plates 12 and 16. Gears 18, driven by a motor M serve to rotate the rolls about their axes.

40 The axes of some or of all of the rolls are skewed with reference to the axis of the center post 14 so that a thread laced about one end of the thread advancing device will, when said rolls are rotated, advance in a spiral path until it reaches the opposite end of said thread storing and advancing device.

45 The assembly thus far described constitutes a thread storing and advancing device which may form part of a continuous process synthetic thread manufacturing apparatus or which may be used for processing synthetic or non-synthetic threads.

50 In the embodiments of Figs. 1 and 6, the axes of the rolls are so skewed that a thread laced

about the thread advancing device will move from right to left as viewed in the drawings.

When the apparatus is used for the manufacture of synthetic thread, a spinnerette 19 is used for emitting an appropriate solution into a precipitating bath 20 to form a filament 22 which is passed over one or more godet wheels 24. After leaving the godet wheel, the filament is wound about the right hand end of the thread advancing device and the rolls are rotated to cause the filament to move spirally from right to left relative to the rolls R1 to R8.

In order to provide for easy and expeditious lacing of the thread onto the thread storing and advancing device, I provide a flat ring 26 which is mounted for rotation about the axis of the center post 14. The ring 26 is located near the thread-receiving or right hand end of the thread advancing device and is rotated so that, when the end of the filament is dropped onto the ring, the thread will form a bundle 28 around the ring. The bundle thus formed is pushed off the ring and onto the adjacent end of the thread advancing device. Due to the skewing of the rolls, the bundle 28 will move from right to left and the trailing filament will form a single file spiral 30 which circumscribes the rolls and which moves longitudinally of the thread advancing device. When the bundle 28 has reached the left hand end of the thread advancing device, it is cut and removed and the trailing end of the filament is threaded onto a coning, twisting, or other take-up device not shown. In order to prevent the filament from entering between the ring 26 and the end plate 12, the ring is provided with an outer vertical guard 32. The ring is prevented from lateral movement by any suitable means such as an inner, vertical, flange 34 which is disposed in the space between the end plate 12 and the adjacent ends of the rolls R1 to R8.

The inside circumference of the ring 26 is larger than the circumference of the thread advancing device and the ring is so mounted as to be free to move up and down, or in a plane normal to the axis of the post 14. By this means, when the ring is moved down to the position of Fig. 4, it will assume an eccentric position relative to the axis of the post 14 in which position the ring 26 rides on one or more of the rolls and is frictionally rotated by contact with the rotating rolls. As shown in Fig. 4, the ring rests upon, and is driven by contact with, the uppermost rolls R1, R2, R3, and R4. This makes for more stability than if the ring 26 were to rest on and be driven by only one or two of the rolls.

When the ring is moved up to the position of Fig. 3, it assumes a concentric position with reference to the axis of the post 14 and it will be out of contact with any of the rolls R1 to R8. In this position the ring 26 does not rotate.

In order to move the ring to either of the positions of Figs. 3 and 4, I provide one or more excentrics 38 which are disposed below the ring 26 and which are adapted to be rotated to the position of Fig. 4, in which the ring 26 rides on the low portions of the excentrics and comes into driving contact with rolls R1 to R4, or to the position of Fig. 3, in which the ring will ride on the high portions of the excentrics, so as to be out of contact with any of the rolls, and will therefore not rotate.

As shown in Fig. 5, the excentrics are mounted on stub shafts 40 which are rotatable, in tandem, by any suitable linkage 42. A handle 44 is provided for actuating said linkage to rotate said ex-

centrics, selectively, to the position of Fig. 3 or to the position of Fig. 4.

In Fig. 6 I have shown the application of the invention to a thread storing and advancing device which is supported at both of its ends instead of being cantilever mounted as shown in Fig. 1. Since the structure of Fig. 6, except for having a supporting frame 10 at each end thereof, is identical with the structure of Figs. 1 to 5, it is deemed unnecessary to describe the structure again.

From the foregoing it will be seen that, to lace a thread onto the thread storing and advancing device, it is merely necessary to turn the excentrics 38 to the position of Fig. 4 and to drop the end of the filament onto the rotating flat ring 26. As soon as a satisfactory bundle 28 has been formed, it is pushed onto the thread storing and advancing device and the excentrics are rotated to the position of Fig. 3. This makes it possible to lace a thread about the cantilever mounted device of Fig. 1, or about the device of Fig. 6 which is supported at both of its ends, with little time, effort or skill. When the difficulty of lacing a thread onto a relatively large cantilever mounted device is remembered, and when the practical impossibility of properly lacing the thread about a device supported at both of its ends, as in Fig. 6, is considered, it will be seen that the lacing ring of my invention constitutes a very important contribution to the art. The difficulties above pointed out are encountered in the lacing of a dry thread and are greatly multiplied when a continuously and rapidly forming filament is to be laced as rapidly as it is precipitated in the regenerating bath in the manner shown in Fig. 1.

My invention also includes means to maintain the proper angle of approach of the thread relative to the rolls and to guard against back-slippage of the thread 22 when the bundle 28 is moved off the ring 26 onto the adjacent ends of the rolls.

As shown in Fig. 1, the godet wheel 24 is mounted for free rotation on a sleeve 46, and is confined against longitudinal displacement by collars 48 at the opposite ends of the sleeve 46. The sleeve 46 is engaged by an arm 50 which is carried by a push and pull rod 52 movable horizontally in a bearing sleeve 53. The rod 52 is provided with a front handle 54 and a back stop 56 and carries an open eyelet 58 for receiving and guiding the filament. The rod 52 also carries a pendent arm 60 the lower end of which is preferably cushioned for pushing the bundle 28 off the lacing ring when the godet wheel is moved to the left by the push rod 52.

The operation is as follows: When it is desired to wind the end of the filament on the lacing ring 26, the rod 52 is pushed to the right, as viewed in Fig. 1, so as to bring the godet wheel and the filament guide 58 into vertical alignment with the ring 26. In this position the pendent arm 60 will be in alignment with the right hand end of the lacing ring. The end of a freshly formed filament, or the end of a thread to be treated, is then wound around the godet wheel, is passed through the eyelet 58, and is allowed to drop onto, and to wind itself about, the rotating lacing ring to form the bundle 28. When the bundle 28 is formed, the operator pulls the handle 54 so as to move the godet wheel, the eyelet 58 and the thread 22 to the left, as viewed in Fig. 1. Simultaneously, the pendent arm 60 pushes the bundle 28 off the lacing ring and onto the adjacent ends of the rolls R1 to R8. The movement of the godet wheel, the guide eyelet 58 and the thread serves to maintain the proper angle of

approach of the thread which would not be the case if the thread were moved off the lacing ring onto the adjacent ends of the rolls without a corresponding movement of the godet wheel or without a corresponding movement of the thread relative to the godet wheel.

What I claim is:

1. A thread storing and advancing reel formed of a plurality of rolls and having a thread receiving end and a thread discharging end, an annular member mounted for rotation near the thread receiving end of the reel and adapted to be engaged, and driven, by the adjacent end of at least one of said rolls, means for rotating said rolls, and means for engaging said member with, or disengaging said member from, said end of said roll.

2. Lacing means for winding a thread about a thread storing and advancing device of the type which includes a plurality of skewed elongated rolls having a thread receiving end and a thread delivering end, and means for rotating said rolls about their axes, said lacing means including a ring mounted for rotation about the axis of said device and movable in a plane normal to the axis of said device to a first position in which said ring is stationary and to a second position in which said ring rotates upon rotation of said rolls, and actuating means for moving said ring to either of said positions.

3. The structure recited in claim 2 in which said ring overlies the adjacent ends of said rolls and, in its said second position is internally engaged and rotated by the end of at least one of said rolls.

4. The structure recited in claim 2 in which said actuating means is in the nature of an eccentric positioned below said ring and rotatable to one position to raise said ring to its said first position, and to a second position to permit the ring to move to its said second position by gravity.

5. Apparatus for treating a thread, said apparatus including a thread advancing device, a ring rotatably mounted near one end of said device and adapted to have the thread wound thereon, means for rotating said ring at will, a finger mounted for movement longitudinally of the axis of said ring, and means for actuating

said finger to push the thread accumulated on said ring onto the adjacent end of said device.

5 6. The structure recited in claim 5 together with a guide in vertical alignment with said ring for directing a thread onto said ring, together with means for moving said guide to a position in alignment with the end of said device simultaneously with the movement of the thread off said ring and onto the adjacent end of said device.

10 7. The structure recited in claim 5 together with a source of thread in alignment with said ring, a guide also in alignment with said ring for directing said thread from said source onto said ring, and means for moving said source and said guide into alignment with said adjacent end of said device simultaneously with the movement of said thread off said ring and onto said adjacent end of said device.

15 8. Means for lacing a thread onto a rotating reel having a thread receiving end and a thread delivering end, said means including a rotatable annular member mounted adjacent the thread receiving end of the reel, means for rotating said annular member, means for preventing movement of said annular member longitudinally of said reel, a thread guide movably mounted above said annular member, and means for moving said thread guide to a first position in which it regis-

20 30 35 ters vertically with and feeds thread onto said annular member and to a second position in which said thread guide registers vertically with and feeds thread onto the receiving end of the reel adjacent said annular member.

HARRY A. KULJIAN.
